MEANS FOR INSERTING A WEFT INTO A
WARP IN A CIRCULAR LOOMHenry James Cooper, High Lane, near
Stockport, EnglandApplication April 1, 1946, Serial No. 658,782
In Great Britain May 16, 1945

4 Claims. (Cl. 139—13)

1

This invention relates to means for inserting a weft into a warp in a circular loom.

According to this invention a circular loom has rotary members which revolve in a circular path and are rotated about their axes and serve to drive waft inserting members through the shed of the warp which weft inserting members are wholly supported by rollers so related and arranged that the warp threads can pass between the weft inserting members and the supporting rollers without having their position or tension materially disturbed.

In one form of the invention the weft inserting members include conical rollers which ride on the supporting rollers.

Preferably rollers on the weft inserting members and cooperating supporting rollers or some of them have peripheral grooves or ribs respectively which cooperate to resist relative displacement in an axial direction.

Means may be provided to reduce the possibility of accidental separation of the weft inserting members from the supporting rollers. These means may comprise magnets travelling with the supporting rollers in a circular path and exerting a downward pull on the weft inserting members.

Preferably the bottom warp threads and the axes of rotation of the supporting rollers are so arranged that if extended they would all meet at a common point on a central line about which the supporting rollers travel, and the peripheries of the supporting rollers and the rollers on the weft inserting members are parts of cones whose apexes also would meet at the said common point.

Each weft inserting member may have two rollers spaced apart in axial alignment and riding on three or four supporting rollers, two of which are arranged spaced apart on a common shaft rotated by gearing, the remaining supporting roller or rollers being rotatable about a different axis or axes from that of rotation of the shaft.

Each weft inserting member may comprise a carriage which has a dropped portion forming or provided with a magnet armature and is formed or provided with an upwardly projecting portion carrying a rotatable bobbin.

In the accompanying drawings—

Figure 1 is a side view in section of a means for inserting weft threads in a warp.

Figure 2 is a fragmentary plan view thereof.

Figure 3 is a side elevation drawn to a larger scale and illustrating a detail.

Figure 4 is a plan view of Figure 3.

Figure 5 is a detached end view in section 55

2

taken on a line corresponding with line 5—5 of Figure 1 and drawn to a larger scale than Figure 1.

Referring to the drawings, in the construction shown more or less diagrammatically therein, I provide a stationary part 1 on which a conveyor 2 is rotatably mounted. The conveyor 2 is rotatable by means of a toothed spur wheel 3 on the conveyor in mesh with a toothed spur wheel 4 provided on a carrier shaft 5 mounted in a stationary bearing 6.

The rotary conveyor is provided with bearings 7 in which are mounted a plurality of horizontal shafts 8 spaced at predetermined distances apart and arranged radially of the post 1. The inner end of each horizontal shaft 8 has a toothed bevel wheel 9 in mesh with a common toothed bevel wheel 10 secured to the post so that when the shafts 8 revolve about the axis of the post 1 in the direction of the arrow 14, Figure 2, each horizontal shaft 8 is caused to rotate about its own axis but in a direction which causes the upper side of the shaft 8 to travel in reverse direction to that of the conveyor.

Each horizontal shaft 8 has two or more rollers, for example two rollers 11 and 12 respectively mounted on it at suitable spaced distances along the shaft, the periphery of each roller coinciding with a different part of a geometrical cone the axis of which coincides with the axis of the horizontal shaft 8 and the apex 13 of which is in the central line 36 coinciding with the axis of the post 1 which in turn coincides with the vertical axis of rotation of the conveyor.

2. Rotation of the conveyor causes the rollers to travel circularly about the central line 36. The rollers 11 and 12 are of different diameters and their diameters are so chosen in relation to the distance of the diameter from the vertical axis of the post 1 that each point on the periphery of each roller 11 or 12, when it reaches its highest position is moving at the same linear speed about the axis of the roller as that at which the said axis moves through its orbit. In Figure 5 the direction of rotation of the conveyor 2 is indicated by an arrow 15, and the direction of rotation of the rollers 11 and 12 is indicated by an arrow 16. Because each point on the rollers 11 and 12 travels in reverse direction to the roller axis during the upper half of its orbit round the roller axis, this equality in speed results in each point when in its highest position, being momentarily stationary in respect to the warp threads and approximating to a stationary

state as it approaches and recedes from the said highest position.

18 are warp threads which converge above the rollers 11 and 12 radially when regarded in plan view and then travel upwards in a direction parallel to the axis of the post 1, the bottom line of warp threads 18 being touched successively by the upper part of the peripheries of the rollers 11 and 12 when the conveyor 2 is rotated. The warp threads of the bottom line if they were extended to the line 36 would meet at the common apex 13 on the line 36.

Because all points on the upper part of the rollers 11 and 12 in contact with the bottom line of warp threads 18 are momentarily stationary in respect to the warp threads or nearly stationary, the rollers 11 and 12 do not shift or bend the warp threads 18 laterally, i. e. in a horizontal direction or twist them to any material extent, but pass them with a substantially rolling motion.

The top line of warp threads 18 is located sufficiently high above the rollers 11 and 12 to accommodate between them and the bottom line, weft-thread carriers 19 each having two or more conical rollers, for example two conical rollers 20 and 21 respectively, which are supported by one of the pair of rollers 11 and 12 provided on each horizontal shaft 8 and are rotated by the said pair of rollers 11 and 12 at the said surface speeds as the said rollers by frictional contact therewith. The rollers 20 and 21 coincide with parts of geometrical cones whose apexes coincide with the common apex 13 of the hereinbefore mentioned geometrical cones. When the rollers 20 and 21 roll over the warp threads 18 of the bottom line the said threads are supported by the rollers 11 and 12. Because all points on the peripheries of the rollers 20 and 21 in contact with the supporting rollers 11 and 12 are rotated by the rollers 11 and 12 at the said surface speed and in the same direction as the part of the rollers 11 and 12 with which they are in contact and all those points on the peripheries of the rollers 20 and 21 which are in the immediate vicinity have approximately the same motion as the said points, all the said points are approximately stationary and therefore ride over the said warp threads 18 without displacing them in a horizontal direction or twisting them to any material extent. The carriage 19 is positively constrained to travel with the rollers 11 and 12 in a concentric circular path round the post 1 by means of two driving rollers 22 and 23 respectively mounted on spindles 24 on the conveyor 2 so as to project somewhat beyond the peripheries of the supporting rollers 11 and 12 and thereby form with their peripheries abutments acting on the peripheries of the rollers 20 and 21. The peripheries of the driving rollers 22 and 23 also coincide with geometrical cones having their apexes coincident with the common apex 13 of the hereinbefore mentioned cones, and are driven frictionally by the rollers 20 and 21 and therefore the driving rollers 11 and 12 and the rollers 20 and 21 have no material shifting or horizontal bending or twisting effect on the warp threads 18 momentarily between them. In the shown construction the driving rollers 22 and 23 are also supporting rollers.

The weight of the carriage 19 acts to cause it to ride on the supporting rollers 11 and 12 and the warp threads 18 and also to prevent the rollers 20 and 21 from jumping over the driving rollers 22 and 23. This action is reinforced by a

permanent, U-shaped magnet 25 provided on the conveyor 2 beneath the bottom line of warp threads 18 and acting on a dropped part 26 of the carriage 19 adapted to serve as an armature, there being an air gap between the magnet 25 and the part 26 of the carriage to accommodate the warp threads 18 of the bottom line. Annular peripheral grooves 27 are provided in the rollers 11 for engagement by annular peripheral ribs 28 on the rollers 20 to prevent axial displacement of the rollers 20 on the rollers 11.

There are as many carriages 19 as there are horizontal shafts 8 and each carriage 19 carries a supply of weft thread 31 by any suitable means 15 such as a bobbin 29 rotatably mounted on a bracket 30 provided on the carriage 19, so that the weft thread 31 can be laid in the shed of the warp threads 18 by playing itself out as the carriage 19 travels in the shed transversely of the warp threads 18.

In operation, assuming the bobbins 29 on the carriage 19 to be charged with weft thread 31 and the carriages 19 to be in position on the rollers 11 and 12 of the conveyor 2, and the conveyor wheel 3 to be driven, the horizontal shafts 8 revolve concentrically round the axis of the post 1 and at the same time, each horizontal shaft 8 rotates about its own axis due to the provision of the bevel wheels 9 and 10. As 30 the conveyor 2 rotates in the direction indicated by the arrow 14 in Figure 2 and by the arrow 15 in Figure 5, the horizontal shafts 8 and their rollers 11 and 12 rotate in the direction indicated by the arrow 16 in Figure 5. Because the carriages 19 are wholly supported by the rollers 11, 12, 22 and 23, they revolve with the horizontal shafts 8 about the axis of the post 1 whilst their rollers 20 and 21 are rotated by the rollers 11 and 12 in reverse direction to the latter rollers, namely 40 in the direction indicated by the arrow 32, and the rollers 20 and 21 rotate the driving rollers 22 and 23 in the same direction as the rollers 11 and 12, namely in the direction indicated by the arrow 33, the surface speeds of each roller 11 and 12, the rollers 20 and 21 and the driving rollers 22 and 23 in contact with the rollers 20 and 21 being equal.

Each radial warp thread 18 has a longitudinal movement caused by being taken up and a vertical movement caused by being shedded and is supported whilst in the bottom line of the shed by each of the rollers 11 and 12 and driving rollers 22 and 23 as it passes beneath the thread 18 and is rolled over by each of the carriage rollers 20 and 21, without however being materially bent or twisted, because the surface speed of rotation of the rollers is equal to and in the vicinity of the shedded warp threads opposite in direction to the speed of revolution of the rollers 11 and 12 about the axis of the post 1.

Each carriage 19 therefore travels through the shed without material bending or twisting of the warp threads 18 and each carriage 19 deposits successively a weft thread 31 in each part thereof, thus converting the warp and weft threads into a woven fabric, there being a plurality of weft threads being deposited simultaneously in the warp.

Presser wires or discs 34 may be provided on 70 the carriages 19 to be driven thereby through the shed and so act on the deposited weft threads after they have been trapped by shed changes as to force each weft thread 31 inserted by preceding carriages 19 towards the previously inserted weft threads. It should be understood

however, that in interpreting the claims herein-after set out any reaction produced by such presser wires or discs on the weft inserting members (which reaction may tend to support the same to a slight extent) is to be disregarded. A weft thread guide 35 of U cross section and provided on each carriage 19 guides each weft thread 31 to the line of the shed. Drag means such as tensioning wires or fur may be provided in the guide 35.

The hereinbefore described mechanism enables weft to be inserted in a warp at a quick rate without the use of any parts which reciprocate or reverse and without damage to and undue strain on and disturbance of the warp threads and weft threads, and by the use of parts moving at relatively slow speeds. The employment of circularly travelling rollers acting as the whole support of the weft inserting members renders the provision of stationary surfaces to wholly or partly support the weft inserting members unnecessary.

The conicity of the rollers on the horizontal shafts 8 act against the centrifugal effect produced on the carriages 19. If the action of the said conicity is insufficient to restrain the carriages from leaving the rollers at the speed it is desired to rotate the conveyor, the shafts 8, instead of being horizontal, may be suitably inclined to the horizontal so as to increase the restraining action of the said rollers. Instead of two separate driving rollers other arrangements may be used; for example there may be a single elongated driving roller for each carriage. As a further alternative instead of two rollers on each carriage, there may, for example, be three or four.

Some or all of the rollers may have a soft or yielding peripheral surface to reduce noise and slip and also liability of crushing of the warp threads between the rollers. The said surface may also assist the warp threads to be passed between the rollers by the rolling action of the rollers. The said surface may be provided by making the rollers of suitably soft material, such as a plastic, or by incorporating therewith a coating of suitably soft material, or a clothing of suitably soft material, such as soft rubber in the form of a renewable sleeve.

I claim:

1. A circular loom having rollers which revolve about a centre line and rotate about their own axes, weft inserting members lying loosely on and supported from below by the said rollers against downward displacement and axial tilting movement, and rollers forming part of and carrying the weft inserting members supported by the first named rollers, the axes of all the rollers being all directed to a common point on the centre line and the peripheries of all the rollers being parts of cones whose apexes also meet at the said common point, and the conicity of the first named rollers resisting the centrifugal effect which acts on the weft inserting members.

2. A circular loom comprising in combination, weft carrying members, two spaced and axially aligned conical rollers on which each weft carrying member is mounted, a plurality of concial supporting rollers situated beneath the first named rollers and supporting them and therefore the weft carrying members against vertical downward displacement and axially tilting over, a rotary and revoluble shaft carrying some of the supporting rollers, and means revolving with the shaft and carrying the remaining supporting

rollers with their axes mounted offset from the said shaft.

3. A circular loom having conical rollers which revolve about a centre and rotate about their own axes and whose tops incline downwards in an inward direction, a plurality of carriages for the weft, conical rollers provided on the carriages and seated on the upper part of the first named rollers which support the whole of the weight of the carriages and second the named conical rollers and simultaneously revolve them about the said centre and resist centrifugal effect acting on the said carriages, dropped portions on the carriages, magnetically attractable means on the dropped portions, an upwardly projecting portion on the dropped portion of the carriage, a rotatable weft thread suporting means carried by the upwardly projecting portions and magnets disposed beneath the said dropped portions for augmenting the gravitational force acting on the said carriages and second named rollers.

4. A circular loom having in combination a plurality of weft carriages, a dropped portion on each weft carriage, a conical running roller provided on each weft carriage beyond one end of the dropped portion, a second conical running roller provided on each weft carriage beyond the other end of the dropped portion in axial alignment with the first named roller, a rotary conveyor, radial, rotary shafts on the conveyor, two conical carrying rollers fixed at a distance apart on each shaft for each supporting a different one of the two running rollers of each weft carriage from below and thereby supporting the weft carriage against falling out of its orbit and tilting axially out of position, co-operating annular grooves and ribs on some of the rollers for preventing the weft carriages from sliding axially on the conveying rollers by gravity or centrifugal effect, two conical abutment rollers mounted on the conveyor and associated with each two conveying rollers and acting on the running rollers for combating the inertia of the weft carriages which acts to cause the weft carriages to remain stationary whilst the conveyor is rotating, a magnetically attractable part on the said dropped portion, and magnets provided on the rotary conveyor beneath each dropped portion for attracting the weft carriages downwardly and thereby forcing the running rollers downwardly towards the upper parts of the conveying rollers and abutment rollers.

HENRY JAMES COOPER.
